[57] **CLAIM**

The ornamental design for a pair of shower shields, as shown and described.

DESCRIPTION

FIG. 1 is a perspective view of a pair of shields showing my new design;

FIG. 2 is a front elevational view of the left shield shown in FIG. 1;

FIG. 3 is a right side view of the left shield;

FIG. 4 is a rear elevational view of the left shield;

FIG. 5 is a left side view of the left shield;

FIG. 6 is a top view of the left shield; and,

FIG. 7 is a bottom view of the left shield.

Views of the right shield in FIG. 1 are mirror images of FIGS. 2 through 7.

The broken line showing is for illustrative purposes only and forms no part of the claimed design.
